UNITED STATES PATENT OFFICE.

THOMAS ROYSTER, OF NEW HAVEN, CONNECTICUT.

SWIMMING DEVICE.

1,137,289.

Specification of Letters Patent.

Patented Apr. 27, 1915.

Application filed June 18, 1914. Serial No. 845,982.

To all whom it may concern:

Be it known that I, THOMAS ROYSTER, citizen of the United States, residing at New Haven, in the county of New Haven and 5 State of Connecticut, have invented certain new and useful Improvements in Swimming Devices, of which the following is a specification.

My invention relates to an improved 10 swimming device, and as its primary object contemplates an attachment for both the ankle and the wrist, such attachment being of a construction whereby to offer little or no resistance to the water when thrust forwardly in the execution of a forward swimming stroke, yet, in the execution of a rearward thrust or stroke, operating or opening automatically to offer a maximum amount of 15 resistance to the water, thus facilitating or aiding the swimmer to an appreciable and material extent.

The above and additional objects are accomplished by such means as are illustrated in their preferred embodiment in the accompanying drawings, described in the following specification and then more particularly pointed out in the claims which are appended hereto and form a part of this application.

In describing my invention in detail reference will be had to the accompanying drawings wherein like characters denote like or corresponding parts throughout the several views, and in which:

Figure 1 is a view illustrating the application of the invention, the devices or attachments being shown affixed to the wrists and ankles of the swimmer; Fig. 2 is an enlarged detail perspective view of one of the devices detached; and Fig. 3 is a section on the line 3—3 of Fig. 2.

Referring now to the drawings by numerals, 1 designates a band, divided longitudinally as shown to advantage in Fig. 2, the adjacent edges of the band being provided with lacing hooks 2 so arranged and attached as to permit of fastening the device to either the wrist or the ankle of the swimmer, one of the said attachments, when in actual use, being fastened to each wrist and to each ankle of the swimmer.

Screws 3 are fastened to the band 1 at substantially diametrically opposite points, the said screws serving as a retaining element whereby the blade or wing of the de-

vice, designated as an entirety by the numeral 4, is held in pivotal relation to the band. Said wing 4 in its preferred embodiment comprises a celluloid body 5, the periphery of which is inclosed by a wire strand 6 of sufficient rigidity to hold the wing or blade 4 against bending or collapsing when in use. The terminals of the wire strand 6 are coiled about the screws or retaining pins 3 as indicated at 7 in Fig. 3 of the drawings, the said pins or screws 3 also serving as a means of attachment for a wire strand 8, bent somewhat after the fashion of the strand 6, and coiled at its terminals as indicated at 9, a washer or like element being interposed between the coils 7 and 9 at the respective terminals of the two strands. Wire strand 8 is disposed to extend in a plane transversely to the longitudinal axis of the band 1, a brace rod or wire strand 10 attached as at 11 to the band and as at 12 to the strand 8 serving as a means whereby the latter is held immovable relatively to the band when blade or wing 4 is pressing thereagainst. The celluloid body 5 of the wing 80 is cut away or longitudinally slotted as indicated at 13 to provide for movement of the blade or wing as the same is moved automatically when in use, from the position shown in Fig. 2 to a position at substantially 85 right angles thereto or approximately parallel with the longitudinal axis of the band. A wire strand 14, affixed in any suitable manner to the strand 8, extends transversely thereof and serves as an abutment for the 90 blade or wing 4 when positioned as shown in the said Fig. 2. Clips or other suitable fastening devices 15 may be provided as a means whereby body 5 is fastened to strand 6 forming the frame or supporting element 95 for the blade. When in use, one of the said devices or attachments is fastened to each wrist and to each ankle of the swimmer, a suitable lacing being utilized as a fastening means. By pivoting the blade or wing of each attachment to the band 1 upon which it is mounted, it is apparent that the said blades or wings will operate automatically 100 to fold or collapse when the arms or legs are thrust forwardly and to open the moment the arms or legs are thrust rearwardly, such movement of the blades, as above set forth, causing a minimum amount of resistance to be offered to the water in the execution of a swimming stroke, and a minimum 105 110

amount of resistance to be offered to the water as the arms and legs are thrust forwardly to prepare for a second swimming stroke.

- 5 From the foregoing, taken in connection with the accompanying drawings it is apparent that the wire strand 8 and the strand 14 mounted thereupon, will serve as an abutment for the wing or blade when opened;
- 10 that the body 5 being slotted, will in no way interfere with or hinder pivotal movement of the said blade; and that by the use of the attachments or devices a swimmer may be made to move faster through the water without a proportionate increase in the exertion incident to swimming.

In reduction to practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention, as defined in the appended claims.

30 Having thus fully described my invention, what I claim as new and desire to secure by Letters Patent, is:—

- 35 1. In a swimming device, an attaching band, a wing pivoted to the band, stop means extending at an angle to the band to limit pivotal movement of the wing, and a guide element for the wing, said element acting as

a brace for the stop means, as and for the purpose set forth.

2. A swimming device including a removable limb-engaging band, a slotted wing pivoted to the band, a frame attached to the band and disposed to extend at an angle to its longitudinal axis, the frame serving as a stop means limiting pivotal movement of the wing, and a brace rod affixed to the frame and the band, said brace rod being adapted to operate within the slot aforesaid to act as a guide for the wing, as and for the purpose set forth.

3. A swimming device including an attaching band, a wing comprising a wing frame pivoted to the band, a body fitting within and fastened to the frame, a portion of the said body being cut away, means carried by the band and extending therefrom at right angles to its longitudinal axis, means holding the said last mentioned means immovable relatively to the band, said last mentioned means operating within that portion cut away of the wing to provide for movement of the latter from a position parallel with the longitudinal axis of the band to a position at right angles to the said longitudinal axis of the band, the said wing 65 when in the latter position being engageable with the said stop means, as and for the purpose set forth.

In testimony whereof I affix my signature in presence of two witnesses.

THOMAS ROYSTER.
